REMOVABLE GRATE FOR STOVES

Filed July 9, 1928

Fig. 1.

UNITED STATES PATENT OFFICE

HERMAN HERRENBRUCK, OF BELLEVILLE, ILLINOIS, ASSIGNOR TO ORBON STOVE CO., OF BELLEVILLE, ILLINOIS, A CORPORATION OF DELAWARE

REMOVABLE GRATE FOR STOVES

Application filed July 9, 1928. Serial No. 291,215.

This invention relates to removable grates for stoves, and an object is to provide a grate for stoves comprising rockable grate sections mounted in such a relationship to each other and to the supporting and enclosing stove structure that the grate sections may be readily removed through the opening to the ash receptacle of the stove.

Another object of the invention is to provide an improved support for the grate bars of a stove, which support may be detached and disconnected from the grate bars so as to permit the grate bars to drop to the ash receptacle from which the said grate bars may be removed without the necessity of removing the top of the stove.

Other objects will appear from the following description, reference being made to the drawing in which

Fig. 1 is a plan view of the base of the stove embodying the present invention.

Figs. 2 and 3 are cross sectional views on the lines 2—2 and 3—3 of Fig. 1, respectively, looking in the directions designated by the arrows at said lines.

The stove base shown comprises walls 1 inclining upwardly from a base flange 2 to integral connection with an approximately inwardly extended horizontal wall or flange 3. A long door opening 4 is formed through the front wall 1 to afford access to the ash receptacle 5. The wall or flange 3 is formed with an upwardly extended flange 6 on its upper side for engagement with the lower end of the wall forming the stove proper (not shown).

Under the wall or flange 3 at one end a supporting bracket is secured. This supporting bracket comprises a plate 7 having an inwardly extended portion 8 from the inner end of which a flange 9 extends upwardly. The plate 8 is secured to the stove base by bolts 10 and the flange 9 is formed with rounded notches 11 which receive the pivot arms 12 on the adjacent ends of the grate sections 13.

The opposite end of one of the grate sections 13 is formed with a long axial member 14 which projects through and is pivotally supported in a hole 15 in the opposite end wall 1 of the base. The other grate bar sec-

tion has an axial projection 16 which is pivotally supported on a downwardly and upwardly curved arm 17 projecting from the side 18 of a supporting member 19. A lug 16^a projecting downwardly and inwardly from the walls 3 and 1 prevents displacement of the projection 16 from the arm 17, and the wall 1 limits endwise movement of the grate section in the direction of the member 14. The supporting member 19 has a projection 20 on one end which is seated in a correspondingly shaped notch in one side of the wall or flange 3; and on its other end the supporting member 19 has a flange 21 seated in a correspondingly shaped notch in one side of the wall or flange 3 and is secured thereto by a stove bolt 22. When mounted in this way one of the grate sections is pivotally supported and held from longitudinal movement in one direction by the arm 17 and the other grate bar is held in proper relationship therewith by contact of the side 18 with the axial pivot member 14. The pivot member 14 projects beyond the stove base a sufficient distance for engagement with a crank or lever whereby it may be rocked. The two grate bar sections are geared together by segmental racks 23 so that they will be rocked in unison.

In the event either of the grate bar sections becomes burned out or otherwise damaged so that it is necessary to remove it and substitute another, such removal and substitution may readily be effected without taking apart or removing the upper portion of the stove (not shown). This is accomplished by removing the bolt 22 and then removing the support 19 permitting the end of the grate section of which the axial pivot 16 is a part to drop to the bottom of the ash receptacle. This grate bar section may then be manipulated to release the arm 12 from the bracket 8 and turned to angular position and removed through the door opening 4.

The other grate bar section may be removed and another substituted by sliding the same longitudinally in a direction to withdraw the axial pivot 12 from the support 9 and then working said bar section to angular position until the axial pivot arm 14 is withdrawn inwardly from the hole 15. Then the

grate bar section may be turned around in the stove base until the end of the axial pivot member 14 extends toward the door opening 4, in which position this grate bar section 5 may be easily withdrawn.

Then other grate bar sections may be inserted into the stove base through the door opening 4 and mounted with their pivots 12 on the support 9, the axial pivot member 14 of one grate section extended through the hole 15, as shown and described, and the axial pivot member 16 of the other grate section mounted upon the arm 17, after which the bolt 22 is replaced and tightened.

15 A grate bar structure of this type and of the dimensions and relationship described is quite an advance over those which require the upper portion of the stove proper to be removed in order to make repairs and replacements in the grate. The construction and arrangement may be varied within equivalent limits without departure from the nature and principle of the invention.

I do not restrict myself unessentially in 25 these or other respects, but what I claim and desire to secure by Letters Patent is:—

1. In a stove, a stove base having an ash receptacle provided with a door opening through one side, a bearing member attached 30 to one end wall of the base within the ash receptacle, a pair of grate sections each having one end supported for rocking movements on said bearing member and one of said grate sections being held from endwise 35 movement in a direction away from said bearing member by the opposite end wall of the base, a bearing supporting the opposite end of said one grate section from said bearing member, an element mounted on said base and supporting said bearing and being removable 40 with said bearing to permit the end of the grate section supported thereby to drop to position for withdrawal through said door opening, an axial member in connection with 45 the other grate section journaled in the end wall of said base adjacent to said bearing and constructed for engagement by a rocker lever, and means for rocking said first grate section by said last mentioned grate section.

50 2. In a stove, a base having a door opening through one side, a bracket attached to one end of said base, a pair of grate sections each having one end supported for rocking movements in said bracket and one of said 55 grate sections being held from endwise movement in a direction away from said bracket by the opposite end wall of the base, a bearing element supporting the opposite end of one grate section from said first named end 60 and being removable to permit the end of said grate section that is supported thereby to drop to position for withdrawal through said door opening, and an axial member in connection with the other grate section journaled in the end wall of said base that holds 65

said first named grate section from endwise movement as aforesaid.

3. In a stove, a base having a door opening through one side, a bracket attached to one end of said base, a pair of grate sections each having one end supported for rocking movements on said bracket and one of said grate sections being held from endwise movement in a direction away from said bracket by the opposite end wall of the base, a bearing element supporting the opposite end of one grate section from said first named end and being removable to permit the end of said grate section that is supported thereby to drop to position for withdrawal through said door opening, an axial member in connection with the other grate section journaled in the end wall of said base that holds said first named grate section from endwise movement as aforesaid and having its end exposed 70 and constructed for engagement by a rocker lever, and means for rocking said first named grate section by said last mentioned grate section.

4. In a stove, upwardly inclined side and end walls forming the side and end walls of a base, an inwardly extended flange integrally united with the upper edges of said walls, a bracket attached to one end of said end walls, a pair of grate sections each having one end supported for rocking movements on said bracket, a bearing element mounted on said flange supporting the opposite end of one of said grate sections and being removable to permit the grate section that is supported thereby to drop downwardly within the enclosure formed by said side and end walls, means in connection with the other grate section for supporting said other grate section for rocking movements, and means for rocking said first grate section by said second grate section.

5. In a stove, a base having a door opening through one side, a supporting bracket secured to the inner side of one end of the base, a pair of grate sections each having one end supported for rocking movements on said supporting bracket, a bearing element supporting the opposite end of one of said grate sections and being removable to permit the end of said grate section that is supported thereby to drop to position for withdrawal through said door opening, means for preventing displacement of said grate section from said bearing element in operative position, means for supporting the adjacent end of the other grate section independently of said bearing element, means for rocking said other grate section, and means for rocking said first grate section by said other grate section.

HERMAN HERRENBRUCK.
